GRANVILLE A. HUMASON, OF HOUSTON, TEXAS.

APPARATUS FOR LOWERING MATERIAL INTO AND WITHDRAWING MATERIAL FROM WELLS.

Application filed June 21, 1926. Serial No. 117,466.

This invention relates to new and useful improvements in an apparatus for lowering material into and withdrawing material from wells.

5 One object of the invention is to provide an apparatus of the character described whereby a load of plastic cement may be lowered into a well bore and discharged therein at a desired point.

10 In carrying on well drilling operations it often becomes necessary to cement around the end of the pipe in the well bore to form a seal therearound to seal off a stratum of water thereabove or below the seal. In some cases a well casing is let down to the bottom of the bore and the cement, in plastic state, is then lowered to the bottom of the bore and discharged so that it will penetrate into the stratum around the lower end of the casing.

15 and when the cement hardens it will form a water tight seal around the casing and hardened cement in the casing may be drilled through and the bore deepened. Also it sometimes happens that casing of a certain diameter is set in the bore and the bore is then reduced with a smaller casing, and it is desirable to form a seal around the joint and in such case the upper end of the lower casing is plugged up with a wooden plug and immediately above the plug the larger casing is slotted and the load of cement is then discharged above the plug, while in plastic state, and will run through the slits and penetrate the surrounding stratum and form a seal around the joint to seal off the stratum of water. When this cement hardens the plug may be drilled through and work continued in the bore beneath.

20 The device herein described has been designed for the purpose of discharging cement, in plastic state, in any desired place in the bore wherever there is a necessity for cementing in or around the casing or pipe.

25 The device may be also used as a bailer for bailing fluid from well bores.

30 With the above and other objects in view this invention has particular relation to certain novel features of construction, operation and arrangement of parts, an example of which is given in this specification and il-

lustrated in the accompanying drawings, wherein:

Figure 1 shows a vertical sectional view of the upper end of the apparatus.

Figure 2 shows a sectional view of the lower end thereof.

Figure 3 shows a cross sectional view taken on the line 3—3 of Figure 1.

Figure 4 shows a cross sectional view thereof taken on the line 4—4 of Figure 1.

Figure 5 shows a cross sectional view of the apparatus taken on the line 5—5 of Figure 2, and

Figures 6 and 7 are vertical sectional views of the upper and lower ends respectively of the apparatus in discharging position and of the form to be suspended in a well bore by the use of a cable.

Referring now more particularly to the drawings, wherein like numerals of reference designate similar parts in each of the figures the numeral 1 designates a tubular barrel whose lower end has a plurality of lateral discharge openings, as 2. Fitted over the lower end of the barrel and slidable thereon there is a tubular sleeve 3 threaded into the lower end of which there is a spider 4 having the openings 5 and upstanding from the spider is a stem 6. Threaded into and closing the lower end of the barrel there is the tubular nipple 7 whose upper end is conical, as at 8. This nipple is substantially tubular with its upper end closed. Within the nipple 7 there is an annular guide 9 through which the stem 6 works and the stem has an enlarged head 10 adapted to engage the guide 9. The sleeve 3 has a plurality of discharge openings 11 and the nipple has oppositely disposed pintles 12, 12, with rollers 13, 13, on their outer ends which run in the corresponding openings 11 and prevent the sleeve from turning on the barrel.

The stem 6 has a series of spaced shoulders 14 which face downwardly and the lower end of the nipple 7 has the oppositely disposed spring dogs 15, 15, whose free ends are adapted to engage underneath said shoulders.

When the device is suspended the sleeve 3 will be in its lowermost position with the head 10 resting on the guide 9 and the dogs 15 en-

100

gaging underneath the upper shoulder 14. In this position the openings 2 will be out of registration with the openings 11, as shown in Figures 1 and 2, and the barrel may then be filled with cementitious material, or cement, in plastic state, which will be retained therein. The apparatus may be attached to a string of pipe, as 16, by means of the collar 17 and thereby lowered into the bore. When the lower end of the sleeve 3 reaches the bottom of the bore, or an obstruction in the casing, as for example, the wooden plug hereinbefore referred to, the downward movement of said sleeve will be stopped and the barrel will move on downwardly by gravity until the openings 2 register with the openings 11, as shown in Figure 7 and the plastic material in the barrel will then be discharged through said registering openings at the desired place in the casing and for the purposes hereinabove stated. As the barrel moves downwardly the nipple 7 and dogs 15 will move downwardly with it relative to the stem 6 and said dogs will engage underneath the lowermost shoulder 14 to thereafter hold the apparatus in open position and during this downward movement the fluid in the sleeve 3, beneath the nipple will pass out through the openings 5. If desired a nipple 18 may be screwed onto the upper end of the barrel and a cable 19 attached thereto for lowering said apparatus into the bore as above described and in such case the upper end of the barrel should be provided with a port 20 to prevent the formation of a vacuum therein when it is attempted to discharge the load. After the load has been discharged, if desired, a certain quantity of fluid may be forced down through the string 16 to wash any plastic material adhering to the walls of the barrel, or, if the form shown in Figures 6 and 7 is employed this fluid may be forced down through the casing and will enter the port 20, as well as the registering openings to flush out said material.

As hereinabove indicated this apparatus may be employed for bailing fluid from wells. When used as a bailer the spring dogs 15 should be dispensed with. When the device is then lowered into the bore and the bottom of the sleeve 3 reaches the bottom of the bore the barrel will move on down until the openings 2 and 11 register, as indicated in Figures 6 and 7. The water in the bore will enter through said registering openings and rise in the barrel to the level of the water in the bore and when the barrel is pulled upwardly, through the string 16, or cable 19, said openings 2 will be carried out of registration with the openings 11 and the water will be trapped

in the barrel and may be withdrawn to the surface of the ground when the apparatus is withdrawn.

What I claim is:—

1. An apparatus of the character described including a barrel having a lateral discharge port, a closure normally closing said port, said closure being movable lengthwise with respect to said barrel to open the port, means preventing the detachment of said closure from said barrel and means for locking said closure in open position, said locking means including a rod anchored to the closure, a nipple in the closure anchored to the barrel, said rod and nipple being provided, one with a dog and the other with means adapted to be engaged by said dog. 65

2. An apparatus of the character described including a barrel whose lower end is closed, said barrel having a lateral discharge opening, a sleeve associated with the barrel and having a lateral discharge opening, each of said members closing the opening of the other when the barrel is in upper position relative to the sleeve, said barrel being movable into lower position relative to the sleeve to bring said openings into registration, a nipple within the sleeve and anchored to the barrel, a rod anchored to the sleeve and extending axially through said nipple, said rod and nipple being provided one with a spring dog and the other with shoulders with which the dog is adapted to engage. 80

3. An apparatus of the character described including a barrel whose lower end is closed, said barrel having a lateral discharge opening, a sleeve associated with the barrel and having a lateral discharge opening, each of said members closing the opening of the other when the barrel is in upper position relative to the sleeve, said barrel being movable into lower position relative to the sleeve to bring said openings into registration and a locking device adapted to permit such movement but to prevent the relative movement of said sleeve and barrel in the other direction, said locking device including a nipple within the sleeve, and anchored to the barrel, means for anchoring the nipple against rotation relative to the sleeve, a rod anchored to the sleeve and extending axially through said nipple, means for preventing the detachment of the rod from the nipple, said rod and nipple being provided, one with a dog and the other with means adapted to be engaged by said dog. 95

In testimony whereof I have signed my name to this specification.

GRANVILLE A. HUMASON.
